SHIELD FOR DIAGNOSTIC REFLECTORS

Julius Brandenburg, New York, N. Y.

Application March 28, 1940, Serial No. 326,366

4 Claims. (Cl. 128—139)

This invention relates to head mirror reflectors worn on the head by physicians for use in the illumination of the ear, nose and throat of a patient.

5 In diagnosing and treating infections, it is highly desirable that the wearer of the reflector be protected against the germs spread by the coughing of the patient and prevent exchange of unpleasant odors from the mouth of the patient and the physician.

An object of this invention is to provide a detachable, boilable disk for reflectors designed to effectively shield the nose and mouth of the diagnostician.

15 Another object of this invention is to provide a nose and mouth shield for reflectors, the said shield being removably mounted on the reflector by mechanism which permits adjustment to a non-shielding position when the shield is not in use and to be retained in tensioned engagement on the reflector in all adjusted positions. When the shield is not in use it acts as a protector for the mirror.

20 Another object of this invention is to provide a detachable shield disk made of rustless material and of a size to completely cover the reflector, the said shield disk having a U-shaped clip made of spring metal pivotally secured thereto and the arms of the clip being designed to resiliently engage the reflector while the disk is retained in tensioned engagement on the clip either over the reflector or over the nose and mouth of the diagnostician.

25 With the above and other objects in view, the invention will be hereinafter more particularly described, and the combination and arrangement of parts will be shown in the accompanying drawing and pointed out in the claims which form part of this specification.

30 Reference will now be had to the drawing, wherein like numerals of reference designate corresponding parts throughout the several views, in which:

35 Figure 1 is a perspective view showing one form of mouth and nose shield embodying my invention in applied position to a head-mirror reflector.

40 Figure 2 is a plan view of the front of the shield.

45 Figure 3 is a side view of the shield and spring clip.

50 Figure 4 is a plan view of an enlarged fragmentary portion of the shield in assembled relation with the spring clip.

55 Figure 5 is a cross-sectional view of the assem-

bled shield, the section being taken as on line 5—5 in Figure 4.

In the illustrated embodiment of the invention, the numeral 10 indicates a head-mirror reflector on which the shield is detachably mounted. The reflector has a central aperture therethrough and is concave on its outer face and of considerable thickness. A head-band 11 is connected to the reflector by a double ball-and-socket universal joint 12 which admit of the reflector being adjusted to any position desired.

The shield 13 is capable of application to the reflector 10 without in any way modifying the construction of the latter, while allowing the necessary adjustment of the shield to protect the 15 nose and mouth of the physician, and the frictional retention of the shield in an elevated position as shown in dot and dash lines in Figure 1.

The shield 13 is preferably made of a disk of aluminum having a dull or non-polished outer 20 surface or other suitable non-reflecting material having a degree of rigidity. The shield 13 has been pivotally connected to a spring clip 14 in a manner to allow lateral adjustment of the shield to a shielding or non-shielding position. 25

As shown in Figure 3, the clip 14 is of substantially U-shaped form, one of the arms 15 extending outwardly slightly more than the arm 16, the portion of the arm 15 projecting outwardly beyond the arm 16 serving to first contact the 30 reflector when assembling, and thereby facilitating the insertion of the reflector between the arms of the spring clip.

As shown in Figure 5, the arm 15 has an aperture 17 in alinement with a circularly dished and apertured portion 18 in the arm 16. The dished portion 18 extends in a direction away from the arm 15 and is of sufficient depth to receive the head 19 of a rivet 20 so that the head will be at or below the inner surface of the arm 16 and prevented from contacting the reflector when the clip 14 is mounted on the reflector. 35

A perforated and axially compressible spring washer 21 has been mounted on the rivet 20 between the disk 13 and the outer face of the arm 16. A flat washer 22 has been mounted on the rivet 20 and in contact with the outer face of the disk 13. The rivet has been clinched so as to compress the spring washer 21 and 40 cause the clip 14 to be held in tensioned relation with the disk 13. 45

50 It is to be noted that the removal of the metal at the perforated portion of the arm 15 prevents the formation of a high spot at the inner surface 55

of the clip. Such a high spot would cause point contact between the clip and the disk, resulting in reduced frictional grip between the clip and the reflector. In the perforated structure shown, there is provided gripping contact at least on an annular area larger than the aperture 17.

In accordance with the patent statutes I have described and illustrated the preferred embodiment of my invention, but it will be understood that various changes and modifications can be made therein without departing from the spirit of the invention as defined by the appended claims.

I claim:

15 1. In combination with a head-mirror reflector, a detachable shield for said reflector, said shield being made of non-reflecting material and of a size to cover said reflector, said shield having a substantially U-shaped spring clip pivotally secured thereto, the arms of said clip being in frictional engagement with said reflector, one of said arms being riveted to said shield, a compressed spring inserted between said arm and said shield to permit tensioned adjustment of 20 said shield relative to said reflector, the arm of said clip opposite said riveted arm having an aperture in alignment with said rivet head, said riveted arm having a circularly dished portion in alignment with said aperture, said dished portion 25 extending in a direction away from said perforated arm and being of sufficient depth to prevent the head of said rivet from contacting said reflector and causing both arms of said clip to grip said reflector on a substantially large 30 area from opposite sides, whereby said shield is retained in tensioned engagement on said reflector in all adjusted positions.

2. In combination with a head-mirror reflector, a detachable shield for said reflector, said shield being made of non-reflecting metal and of a size to cover said reflector, said shield having a spring mounting, said mounting comprising a substantially U-shaped spring clip, the arms of said clip being spaced apart in frictional engagement with said reflector, one of 40 said arms being riveted to said shield, a compressed spring inserted between said arm and said shield to permit tensioned adjustment of said shield relative to said reflector, the arm of said clip opposite said riveted arm having an aperture in alignment with said rivet head, said riveted arm having a circularly dished portion in alignment with said aperture, said dished portion 45 being pressed in a direction away from said perforated arm, said dished portion being of 50

sufficient depth to prevent the head of said rivet from contacting said reflector and causing both arms of said clip to grip said reflector on a substantially large area from opposite sides, whereby said shield is retained in tensioned engagement on said reflector in all adjusted positions. 5

3. In combination with a head-mirror reflector of disk-like form, a detachable shield disk for said reflector, said disk being made of non-reflecting metal and of a size to cover said reflector, said shield having a spring mounting, said mounting comprising a substantially U-shaped spring clip, the arms of said clip being spaced apart in frictional engagement with said reflector, one of said arms being riveted to said shield, a compressed spring inserted between said arm and said shield to permit tensioned adjustment of said shield relative to said reflector, the arm of said clip opposite said riveted arm having an aperture in alignment with said rivet head, said riveted arm having a circularly dished portion in alignment with said aperture, said dished portion being pressed in a direction away from said perforated arm, said dished portion being of sufficient depth to prevent the head of said rivet from contacting said reflector and causing both arms of said clip to grip said reflector on a substantially large peripheral edge from opposite sides. 10 15 20 25

4. In combination with a head-mirror reflector of disk-like form, a detachable shield disk for said reflector, said disk being made of non-reflecting metal and of a size to completely cover said reflector, said shield having a spring mounting at the outer edge thereof, said mounting comprising a substantially U-shaped clip made of spring metal, the arms of which are spaced apart to permit frictional engagement of said reflector, one of the arms of said clip being riveted to said shield, a compressed spring 40 washer inserted between said arm and said shield to permit tensioned adjustment between said clip and said shield, the arm of said clip opposite said riveted arm having an aperture in alignment with said rivet head, said riveted arm having a circularly dished portion in alignment with said aperture, the metal of said dished portion being pressed in a direction away from said perforated arm, said dished portion being of sufficient depth to prevent the head of said rivet 45 from contacting said reflector and causing both arms of said clip to grip said reflector on a substantially large peripheral edging from opposite sides. 50 55

JULIUS BRANDENBURG. 55
